BOTTLE AND CAN CRUSHER

James G. Bryant, 1504 10th St., Port Huron, Mich.

Filed Mar. 1, 1965, Ser. No. 84,023

Term of patent 14 years

(Cl. D55—1)

FIG. 1 is a perspective view of a bottle and can crusher embodying my design.

FIG. 2 is a perspective view of the bottle and can crusher shown in FIG. 1 with the top hood raised.

The side not illustrated is the same as the side shown, and the back is plain.

The broken line showing of a garbage can is for illustrative purposes only.

I claim:

The ornamental design for a bottle and can crusher, substantially as shown and described.
